UNITED STATES PATENT OFFICE.

JAMES A. DAVIS, OF ATLANTA, GEORGIA.

TURBINE WATER-WHEEL.

SPECIFICATION forming part of Letters Patent No. 592,984, dated November 2, 1897.

Application filed October 28, 1895. Serial No. 567,167. (No model.)

To all whom it may concern:

Be it known that I, JAMES A. DAVIS, a citizen of the United States, and a resident of Atlanta, in the county of Fulton and State of Georgia, have invented certain new and useful Improvements in Turbine Water-Wheels; and I do hereby declare the following to be a full, clear, and exact description of the invention, such as will enable others skilled in the art to which it appertains to make and use the same, reference being had to the accompanying drawings, forming a part of this specification.

My invention relates to improvements in the construction of turbine water-wheels, for which Letters Patent of the United States No. 219,348 were granted to me on the 9th day of September, 1879; and the object is to simplify the construction and to increase the efficiency and durability of the same; and to this end the novelty consists in the construction, combination, and arrangement of the same, as will be hereinafter more fully described, and particularly pointed out in the claim.

In the accompanying drawings the same reference-letters indicate the same parts of the invention.

Figure 1 is a perspective view of my improved turbine with the wheel mounted in a horizontal plane. Fig. 2 is a similar view showing the wheel mounted vertically. Fig. 3 is a perspective view of the horizontal casing with the cover-plate and wheel raised a short distance above the casing. Fig. 4 is a side elevation of the wheel. Fig. 5 is a cross-section through the stuffing-box of the main shaft. Fig. 6 is a transverse vertical section through the center of the wheel, the casing, and the valve-box. Fig. 7 is a horizontal section of the same.

B represents the approximately scroll-like shell or casing, and a^2 the bottom plate, which is cast integral with the shell B. The removable top plate or cover a^4 is provided with a scroll-like recess a' , which receives the upper edge of the casing B, the whole being rigidly secured together by the bolts a^3 .

D represents the main shaft, which is cast integral with the water-wheel C. The lower end of the shaft D is formed with a countersunk recess d to receive the bearing-stud f ,

secured in the boss f' of the bearing-lever F, which is fulcrumed in the depending bracket G, and its opposite end extends through a depending guide-bracket G' , its immediate end engaging the stirrup h on the supporting-rod H, which extends upwardly through a lug on the cover a^4 , its threaded end receiving a nut h' , by means of which said supporting-lever F may be adjusted to compensate for the wear and tear on the bearing at the bottom of the shaft D.

The water-wheel C is eccentrically mounted in the shell or casing B and immediately over the discharge-opening E and concentric therewith. The integral depending flanged buckets C' project into the opening E, the downwardly-inclined faces of which receive the full weight of the water as it leaves the wheel proper.

E' represents a cylindric collar pendent from the bottom plate a^2 and forming a continuation of the discharge-opening.

The integral radial buckets c are formed with spiral outer edges and radial plane faces, which receive the first full impact of the water, after which the radial V-shaped openings between the buckets c furnish a free discharge for the spent water and allow it to fall by gravity on the inclined faces of the depending flanged buckets C' to impart additional force to the wheel.

N represents the gate box or housing, which is formed at its inner side with a continuous flange O and is open at one end and formed with a surrounding flange o.

o' represents the outer side wall of the housing, which closes one half of that side, leaving the remaining half open, and around this opening is a flange o^2 , to which the flange N^2 of the wood trunk box or socket N' is bolted.

O' represents an attaching and division plate provided at one end with an opening for passage of the water from the gate-housing into the wheel-casing and at the other end with a lateral flange p. This plate is attached to the flange O by bolts t and to lateral flanges a^5 on the scroll-shell B by bolts t' .

The side wall o' of the gate-housing is extended to form an inwardly-projecting flange o^3 , which forms a chamber o^4 at one side of the water-passage for the gate Q. This gate

is provided with rack-teeth which mesh with a pinion R on a shaft R'. The open outer end of the housing which leads into the gate-chamber is closed by a plate q, attached by 5 bolts q' to the flanges o² p. By detaching this plate access may be readily had to the housing to repair, remove, or replace the gate without taking the entire casing apart.

As will be seen by reference to Fig. 6, the 10 gate-box contiguous to the parallel face of the casing o is formed with rabbeted guide-recesses P, which receive the vertical flanged edges of the gate and serve to hold it in place when operated by the pinion on the shaft R'.

15 In the modification shown in Fig. 2 the construction is practically the same, except that the shell and wheel are mounted vertically and an elbow shown in the right of the figure is provided to conduct the spent water off 20 from the wheel.

Having thus fully described my invention, what I claim as new and useful, and desire to secure by Letters Patent of the United States, is—

25 In turbines, the combination of the casing comprising a bottom plate a² having a discharge-opening, a top plate a⁴, and a scroll-like shell or surrounding wall B provided at

its ends with the lateral flanges a⁵, a wheel 30 mounted on a shaft having bearing in said casing, a gate-housing N open at its inner side and one end and provided with the surrounding side flange O and end flange o² and vertical wall o' at its opposite side leading from said open end to a point about midway 35 thereof and provided with the inwardly-extending flange o³ forming the gate-chamber o⁴, an attaching and division plate O' bolted to the flanges a⁵, O, and provided at one end with an opening for passage of the water 40 from the gate-housing into the casing and at the opposite end with a lateral flange p, a gate Q inclosed in the gate-chamber o⁴ and adapted to be moved to close the water-passage, and a plate, q, detachably connected 45 with the flanges o², p, at the open end of the gate-housing, whereby access may be had to the gate-chamber by simply detaching said plate, substantially as described.

In testimony whereof I affix my signature 50 in the presence of two witnesses.

JAS. A. DAVIS.
